(57) **CLAIM**

The ornamental design for a cooking utensil stand, as shown and described.

DESCRIPTION

FIG. 1 is a perspective view of a cooking utensil stand, showing my new design, shown in environmental use;

FIG. 2 is a top perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is a perspective view thereof, shown without the top casing for ease of illustration, shown in environmental use;

FIG. 10 is a top perspective view thereof, shown without the top casing for ease of illustration;

FIG. 11 is a rear view thereof, shown without the top casing for ease of illustration;

FIG. 12 is a top view thereof, shown without the top casing for ease of illustration;

FIG. 13 is a bottom view thereof, shown without the top casing for ease of illustration; and,

FIG. 14 is a right side view thereof, shown without the top casing for ease of illustration.

The broken lines in the figures illustrate the portions of the cooking utensil stand that form no part of the claimed design. The broken line showing of the cooking utensils, stand, and tray in FIGS. 1 and 9 is for the purpose of illustrating environmental subject matter that forms no part of the claimed design.

The dot-dash broken lines immediately adjacent to the claimed areas in FIG. 5 represent the boundaries of the design and form not part thereof.
